UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

COUNTING-MACHINE.

1,385,410.

Specification of Letters' Patent. Patented July 26, 1921.

Application filed April 20, 1920. Serial No. 375,198.

To all whom it may concern:

Be it known that I, CURTIS HUSSEY VEEDER, a citizen of the United States, residing in the city of Hartford, in the State 5 of Connecticut, have invented certain new and useful Improvements in Counting-Machines, of which the following is a specification, reference being had to the accompanying drawing, forming a part hereof.

10 In another application for Letters Patent of the United States, Serial No. 374,085, filed April 15, 1920, there is shown and described a counting machine in which the transmission of motion from the actuating 15 shaft to the re-setting, by which the number wheels have been moved in counting operations or re-set to zero, is effected through a form of transmitting devices in which the actuating shaft is made to actuate a pivotally mounted gear segment through the oscillation of which the re-setting shaft is actuated. In that application two different 20 embodiments of the invention are shown and one of them is claimed specifically. In 25 the present application it is intended to cover the other specific embodiment of the broad invention. The invention will be more fully explained hereinafter with reference to the accompanying drawing in which 30 it is illustrated and in which—

Figure 1 is a view in elevation of a counting machine in which the invention is embodied, the casing being partly broken away to show parts within.

35 Fig. 2 is a view in transverse section on the plane indicated by the broken line 2—2 of Fig. 1, looking in the direction of the arrows.

Fig. 3 is a partial view in longitudinal 40 section on the plane indicated by the broken line 3—3 of Fig. 2, looking in the direction of the arrows.

Fig. 4 is a partial view in longitudinal section on the plane indicated by the broken 45 line 4—4 of Fig. 2, looking in the direction of the arrows.

The numbering mechanism may be of any usual or suitable construction, the present invention not being directly concerned therewith. So far as the same is represented in the drawing it may comprise a numbering shaft shown at a in Fig. 1, with an arm a' for connection to the part the movements of which are to be counted, a series of number 50 wheels mounted upon a common axis, a pawl 55

frame (not shown) by which the number wheels are driven forward, hold pawls indicated at a^4 , and a re-setting shaft b , which is seated at one end in the end of the shaft a , constitutes the common support for the 60 number wheels, and is provided with means, known in the art, by which, through the oscillation of the re-setting shaft, those number wheels which have been moved in successive counting operations are reset to 65 zero when the counting operation has been completed. All of the parts thus far referred to, including the devices actuated by the re-setting shaft for setting the number 70 wheels to zero, may be of any usual or suitable construction, the present invention being concerned with the means for actuating the re-setting shaft b .

In the construction shown, the end wall c' of the casing c is provided with a hub c^2 75 to form a bearing for the actuating shaft d , which has secured to it a suitable finger piece d' for operation by the finger. The shaft d , within the casing, is formed with a socket to receive the reduced end of the 80 re-setting shaft b and is flanged as at d^3 on opposite sides of the axis, the flanges being guided in an aperture e' of a plate e . Each flange is formed with a pin or lug d^4 which engages the radial slot h' of a gear 85 segment h^2 . The gear segments engage the teeth b' and are pivoted on pins g^3 of a plate g which is carried by pins g^2 , which enter apertures e^2 in ears e^3 of the plate e , so that limited sidewise movement of the 90 plate g and therefore of the gear segment h^2 is permitted. In operation of the construction shown, the oscillation of the shaft d , under the pressure of the operator's finger, effects oscillation of the gear segments h^2 , 95 through the engagement of the pins d^4 therewith, and a consequent oscillation of the re-setting shaft b , the parts being so proportioned that an oscillation of the actuating shaft d to a comparatively small angle is 100 sufficient to effect an oscillation of the re-setting shaft sufficient to return all of the number wheels to zero, even if they have been moved through nine steps.

I claim as my invention:

1. In a re-setting mechanism for a numbering machine, the combination of a toothed re-setting shaft, an actuating shaft, and a pivotally mounted gear segment engaging the re-setting shaft, the actuating shaft and 110

- the gear segment having a pin and slot engagement whereby the gear segment is oscillated through oscillation of the operating shaft.
- 5 2. In a re-setting mechanism for a numbering machine, the combination of a toothed re-setting shaft, an actuating shaft, supporting means mounted with freedom for limited sidewise movement, and gear segments pivotally mounted on said supporting means in engagement with the re-setting shaft, the gear segments having pin and slot connection with the actuating shaft, whereby the gear segment is oscillated through oscillation of the operating shaft.
- 10 3. In a re-setting mechanism for a numbering machine, the combination of a toothed re-setting shaft, an actuating shaft, a pivotally mounted gear segment, and a supporting plate for the gear segment, the gear segment and the actuating shaft having a pin and slot connection whereby the gear segment is oscillated through oscillation of the operating shaft.
3. In a re-setting mechanism for a num-

bering machine, the combination of a toothed re-setting shaft, an actuating shaft, supporting means mounted with freedom for limited sidewise movement, and gear segments pivotally mounted on said supporting means in engagement with the re-setting shaft, the gear segments having pin and slot connection with the actuating shaft, whereby the gear segment is oscillated through oscillation of the operating shaft.

This specification signed this 16 day of April, A. D. 1920.

CURTIS HUSSEY VEEDER.
